DOOR LATCH

Application filed March 14, 1930. Serial No. 435,851.

This invention relates to latches for doors and the like and more particularly to such as are used on automobile doors.

A primary object of the invention is to provide a simple and efficient door latch which will securely hold the door in closed position without possibility of rattling and which is noiseless in its opening and closing operations.

In carrying out these objects, the invention is susceptible of a wide range of modification without departing from the spirit of the invention or sacrificing any of the advantages of the claimed invention; there being shown in the drawings for illustrative purpose a preferred and practical form, in which:

Figure 1 represents a front elevation of a latch constructed in accordance with this invention shown applied, the view being taken from the inside of an automobile;

Fig. 2 is a front elevation or edge view of the latch member which is carried by the closure in connection with which it is to be used with the parts shown in normal locked position;

Fig. 3 is a similar view with the parts shown in unlocked or inoperative position;

Fig. 4 is a vertical section showing the latch applied and in closed position;

Fig. 5 is rear elevation of the latch taken from the open side of the closure housing in which it is mounted;

Fig. 6 is a detail perspective view of a latch operating cam and its connected parts shown detached;

Fig. 7 is a horizontal section taken on the line 7—7 of Fig. 5;

Fig. 8 is a view similar to Fig. 5 with the parts shown in the position assumed when the latch is retracted;

Fig. 9 is an enlarged detail view of the upper portion of the latch with the cam shown revolved from the position shown in Fig. 8; and

Fig. 10 is a detail perspective view of the locking cam detached.

In the embodiment illustrated the latch constituting this invention and indicated as a whole by the numeral 10 is shown mounted on an automobile door 1 with a cooperating

complementary keeper 3 secured to the body of the automobile 2 in the door opening thereof in the usual manner and provided with a transversely arranged cam bar 3a for a purpose presently to be described.

The door 1 is cut out at its front edge to receive the latch carrying housing 11 which is shown substantially U-shaped in cross section, being open at its top and bottom and along its rear edge which latter is designed to fit within the door opening and be secured to the door by bolts 12.

A shaft 13 which carries the door knobs extends through the housing 11 and has fixed thereto within said housing a yoke-shaped cam 15 including as a part thereof a block 16 having a bore 17 through which the shaft passes and which is secured to the shaft by means of a set screw or bolt 18. This cam 15 has hook-shaped legs 19 tapering toward their terminals, the yoke-shaped portion or body of the cam increasing in width towards its central portion with the front edge 20 thereof normally engaging the periphery of a hollow roller or sleeve 21a revolvably mounted on a stub shaft or stud 21 which projects laterally from the inner face of the upper end of a bolt carrying arm 22 pivoted at 23 at its lower end to the front wall of the housing 11 as is shown clearly in Figs. 4 and 5 also in Fig. 8. This arm 22 is made in the form of a heavy metal plate of a thickness sufficient to resist the strain to which it is subjected and of a length sufficient so that when swung on a pivot its free bolt-carrying end will move through an arc of a circle for a purpose to be described.

At the upper end of this arm or plate 22 on the outer face thereof are two laterally projecting bolts 24 and 25 which operate in transversely extending slots 26 and 27 formed in the front face of the housing 11 as is shown clearly in Figs. 2 and 3. These locking bolts 24 and 25 are longitudinally spaced from each other on the arm 22 and arranged out of longitudinal alignment as are also the openings 26 and 27 in the housing through which they operate.

A stiff coiled spring 28 is connected at one

end by means of a link 29 with the yoke-shaped cam 15 at one side thereof, a loop or eye 30 being here shown provided to effect this connection.

5 The other end of the coil spring 28 is connected with a cross rod or bolt 31 extending through the side members of the housing at the lower ends thereof. This spring 28 is placed under tension when the cam carrying shaft or shank 13 is turned in either one direction or the other by means of the knobs 14 and operates to return the shaft to normal position after the knobs are released.

10 15 A substantially U-shaped bar 32 is mounted in the housing with the legs thereof bolted or otherwise secured to the side members of the housing and with the cross bar spaced from the front wall of the housing a sufficient distance to permit the arm 22 to move freely 20 back and forth between it and said wall and which operates to prevent said arm from getting out of place.

25 Arranged between one edge of the arm 22 and the adjacent side wall of the housing are a plurality of coiled springs 33, three of which are here shown, although obviously any desired number may be employed and which exert their tension to move the arm away from the side wall of the housing 30 against which the springs bear after it has been forced towards said side wall by turning of the shaft 13 in a manner presently to be described.

35 These springs 33 have one end inserted in 40 sockets in the edge of the arm 22 as is shown clearly at 34 in Fig. 6 and by means of which said springs are reliably retained in operative position.

45 The cam bar 3a is arranged transversely of the door frame in position to extend between or be straddled by the bolts 24 and 25 when the door is closed. The swinging of these bolts in the arc of a circle causes them to grippingly engage the upper and lower edges of the bar 3a when the door is closed as shown in Figs. 1 and 2 so that any force exerted to open the door without turning shaft 13 will cause the bolts to more firmly grip the bar and thus prevent such opening. 50 The turning of one of the knobs 14 and the consequent turning of shaft 13 will through the means above described move the bolts 24 and 25 so that they will parallel the upper and lower edges of the bar 3a and thus permit the door to swing freely out to open position.

55 It will thus be seen that when the shaft 13 is turned in either one direction or the other by means of the knobs 14 the cam 15 will be turned with it and the cam edge 20 thereof engaged with the sleeve 21a will operate to move the arm 22 edgewise against the tension of the springs 33 thereby causing the locking bolts 24 and 25 to move transversely 60 of the housing through the slots 26 and 27

into paralleling and disengaging relation to bar 3a thus unlocking the door. The springs 33 and the spring 28 operates to hold the bolts normally in locking position. As shown these locking bolts 24 and 25 extend into 70 sockets in the keeper member 3 carried by the body of the automobile or of the door frame and are held yieldingly engaged with bar 3a located therein by means of the springs above mentioned, and not only securely lock the door, but also prevent all possibility of rattling of the parts. This construction owing to the gliding of the bolts on the cam bar, 75 also prevents any clicking of the door when it is shut thus providing a noiseless latch whereby the door may be closed and locked softly without slamming and which may be readily opened by simply turning one of the knobs in either direction, up or down.

80 85 This latch is not only noiseless and effective in its operation but is simple and cheap to manufacture and has few parts to get out of order and when one of the springs becomes depleted or broken in any way it may be very easily replaced, the other parts of the device being practically wear proof. The yoke 15 is adjustably mounted on the shaft or shank 13 by means of the set screw or bolt 18 so that in case there should be wear between this member and the operating stub 90 shaft 21 the cam may be adjusted to compensate for this wear.

95 100 Without further description it is thought that the features and advantages of the invention will be readily apparent to those skilled in the art, and it will, of course, be understood that changes in the form, proportion and minor details of construction may be resorted to, without departing from the spirit of the invention or its scope as claimed. 105

I claim:

110 1 A door latch comprising a supporting structure, an arm pivoted to oscillate on said structure and normally urged to swing in one direction, a locking member carried by said arm, a door knob having a shank mounted to turn in said structure, a cam mounted on said shank, a cooperating element carried by said arm in the path of said cam adapted to be engaged by the cam on the turning of the shank to move said arm into unlocking position, said cam being adjustable on said shank to compensate for wear when necessary, and means to return said knob to normal position when released.

115 120 2. In a door latch a supporting structure, an arm pivoted to oscillate on said structure, a locking member carried by said arm, a door knob having a shank mounted to turn in said structure, a yoke-shaped cam straddling said shank, and fixed thereto to turn with the shank, a projection on said arm extending into the path of said cam whereby the turning of the shaft will move said arm into locking position, said yoke-shaped cam 125 130

having means for engagement with said projection to limit the locking movement of the arm.

3. In a door latch the combination of a housing, an arm pivoted at one end to move edgewise in said housing, springs for cushioning the movement of said arm in one direction, and for urging it in the other direction, a locking element carried by said arm, a slot in said housing through which said locking element projects, a door knob having a shank mounted to turn in said housing, a yoke shaped cam straddling said shank and adjustably mounted thereon, a projection carried by said arm in the path of said cam whereby the turning of said shank will operate to move said arm into unlocking position, and a coiled spring connected with said cam and housing for returning the shank to normal position when the knob is released.

20 4. In a door latch, a supporting structure, an arm pivoted to oscillate on said structure, laterally projecting longitudinally spaced bolts carried by the free end of said arm, a bar to be mounted on a support and cooperating with said bolts to lock them together, said bar being straddled by the bolts and grippingly engaged on opposite edges thereby when the arm is swung in one direction, said bar being released when the arm is swung in the opposite direction.

25 5. In a door latch, a supporting structure, an arm pivoted to oscillate on said structure, laterally projecting longitudinally spaced bolts carried by the free end of said arm and arranged in planes spaced laterally from each other, and a bar to be mounted on a support and cooperating with said bolts to lock them together, said bar being straddled by the bolts and grippingly engaged on opposite edges thereby when the arm is swung in one direction, said bar being released when the arm is swung in the opposite direction.

30 6. In a door latch, a supporting structure, an arm pivoted to oscillate on said structure, laterally projecting longitudinally spaced bolts carried by the free end of said arm and adapted to swing therewith in an arc of a circle, said bolts being arranged in planes extending longitudinally of the arm and spaced laterally from each other, and a bar to be mounted on a support and cooperating with said bolts to lock them together, said bar being straddled by the bolts and grippingly engaged on opposite edges thereby when the arm is swung in one direction, said bar being released when the arm is swung in the opposite direction, and means for automatically swinging said arm into locking position.

JAMES J. PIPER.
